UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

Application filed December 16, 1926. Serial No. 155,122.

This invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter elevated and returned through distributing mechanism to the magazine from which they started. More particularly, it relates to that class of linotype machines equipped with a plurality of magazines mounted in or carried by a so-called "shift frame", which is movable upwardly and downwardly in the machine frame to bring one or another of the magazines into operative relation to the assembling and distributing devices. In the commercial machines of this type, the shifting of the magazines is accomplished by means of screw mechanism controlled by a hand crank conveniently located at the front of the machine. While this arrangement is thoroughly practical, the operation has always been slow and tedious and more or less laborious.

The present invention contemplates the use of power for raising and lowering the magazines, and the mechanism herein provided not only presents many advantages over prior devices but is particularly valuable as a commercial proposition, owing to its ready applicability to the standard and outstanding machines. In the preferred embodiment illustrated, the inclined shaft ordinarily employed for rotating the magazine elevating screw is operatively connected to a compact self-contained reversing gear mechanism which is arranged at the front of the machine and is driven directly by the fore-and-aft assembler drive shaft common to all linotype machines.

In the accompanying drawings, the invention has been shown merely in preferred form and by way of example, and obviously many changes and variations may be made therein and in its mode of adaption which will still be comprised within its spirit. It is to be understood, therefore, that the invention is not limited to any specific form

or embodiment except in so far as such limitations are specified in the claims.

Referring to the drawings:

Fig. 1 is a side elevation of a portion of a linotype machine equipped with the present improvements;

Fig. 2 is a detail sectional view through the friction coupling of the lay shaft;

Fig. 3 is an enlarged vertical section taken on the line 3—3 of Fig. 1; and

Figs. 4 and 5 are sections taken, respectively, on the lines 4—4 and 5—5 of Fig. 3.

The several magazines A are mounted upon the separate base frames A¹ conjointly constituting a "shift frame", which is arranged to be moved upwardly and downwardly in the fixed machine frame to bring any selected one of the magazines into operative relation to the assembler entrance B and the magazine entrance C, the latter leading from the distributor D and serving to conduct the matrices to their proper magazine channels. The release of the matrices from the operative magazine is controlled in the usual way from the keyboard E through the medium of reeds and levers, not shown. The magazine "shift frame" (Fig. 1) is carried by the sliding plunger A² which is mounted in the sleeve O secured rigidly to the main frame, and which engages the screw F geared at its lower end to the inclined shaft F¹, the arrangement being such that the rotation of said shaft in one direction or the other turns the screw in a corresponding direction and causes it to raise or lower the shift frame. At its forward end, the shaft F¹ is provided with the horizontal extension F² supported in suitable bearings at the lower end of the intermediate bracket O¹ and which, as it so happens, is arranged a short distance below and parallel to the fore and aft shaft G also supported by the bracket O¹. This shaft G is common to all machines of the present type, being geared at its rear end to the well-known constantly driven "intermediate shaft" H and provided at its forward end with the usual pulley G¹ which drives the assembling devices.

In order to insure transverse registration of the individual magazines with the assembler entrance B and the magazine entrance C, two pairs of gauge bars are provided and arranged at opposite sides of the magazines, the bars J, J¹ of each pair being notched at j and rigidly connected together by an inter-

- vening piece J^2 . These bars are supported at their lower ends upon the plain aligning surfaces J^3 of the fixed machine frame and present their upper ends in position to engage the under sides of the aligning lugs A^3 projecting laterally from the opposite sides of the magazine base frames A^1 at both ends thereof. When any selected magazine is brought into operative position, the aligning lugs A^3 of its base frame will be caused to bank upon the gauge bars J, J^1 , which thus arrest the magazine in proper transverse registration with the assembler entrance B and the magazine entrance C , respectively.
- 15 In providing for the engagement of the gauge bars J, J^1 with the aligning lugs A^3 , the former are arranged to slide forwardly and rearwardly on the fixed aligning surfaces J^3 so as in one position to stand clear 20 of the aligning lugs during the shifting of the magazines, and in the other position to stand beneath the lugs of the selected magazine base frame, the movement of the gauge bars being controlled by the hand lever J^4
- 25 through the pair of arms J^5 rising from the rock shaft J^6 and operatively connected at their upper ends to the bar connecting pieces J^2 . With this arrangement, when it is desired to substitute another of the several 30 magazines for the one being used, the shift frame is raised slightly to relieve the gauge bars of the weight of the operative magazine, so that by depressing the hand lever J^4 the gauge bars may be drawn forwardly 35 against the tension of their actuating springs j out of the path of the magazine aligning lugs A^3 . After the magazines have been raised or lowered to approximately the position desired, the handle J^4 is released to 40 allow the bars to resume their active position beneath the aligning lugs of the magazine selected, whereupon the shift frame is lowered slightly until the lugs engage the bars, which thus support the selected magazine 45 in operative position. The parts so far described, except as hereinafter specified, are or may be the same in form and mode of operation as those embodied in the commercial Model 8 linotype and in themselves constitute 50 no part of this invention.
- According to the present invention, the raising and lowering of the magazines is accomplished by means of a reversible gear mechanism which is driven directly by the assembler drive shaft G before mentioned, and which is controlled by a positive clutch device conveniently located adjacent the keyboard E . As shown in Figs. 1, 3 and 6, the proposed gear mechanism is supported in a 55 cast iron bracket L having an upright portion L^1 and a rearward extension L^2 , the latter serving as a bearing for the forward horizontal extension F^2 of the lay shaft F^1 . Preferably, the bracket L is secured to the 60 front side of the intermediate bracket O^1

near the lower end thereof in precisely the same place as that occupied by the bearing bracket ordinarily employed to support the shaft extension F^2 , the same screw bolt M and dowel pin M^1 being also utilized to hold it in position. Thus, in attaching the proposed gear mechanism to the machine, it is merely necessary to remove the old bearing bracket and substitute the bracket L therefor, this being accomplished without changing the structural details of the machine framework.

Arranged within the lower end of the upright portion L^1 and loosely mounted on the shaft extension F^2 are reversing bevel gears L^4, L^5 , which are in constant mesh with a bevel gear L^6 fixed to the lower end of an upright inclined shaft L^7 also journaled in the bracket L . At its upper end, the shaft L^7 is provided with a bevel gear L^8 keyed thereto and meshing with a corresponding driving gear G^2 mounted on the fore and aft shaft G in front of the assembler drive pulley G^1 . Motion is transmitted to the lay shaft F^1 from the fore and aft shaft G and gear G^2 by a clutch L^9 , preferably of the jaw or claw variety, which is splined to the horizontal extension F^2 between the reversing gears L^4, L^5 and is adapted by a slight axial movement in one direction or the other to engage corresponding claw members L^{10}, L^{10} , fixed to said gears respectively. As best shown in Figs. 3 and 5, the operation of the clutch is effected by means of a fork L^{11} which engages an annular groove or recess in the clutch and is eccentrically attached to a short rock shaft L^{12} disposed at right angles to the shaft extension F^2 . This shaft L^{12} is journaled in the lower end of the bracket L and is provided at its free end with an upright crank arm L^{13} operable back and forth by a small handle or control button L^{14} . The parts are so arranged (see dotted lines, Fig. 5) that in the vertical position of the crank arm, the clutch L^9 stands disengaged from both gears L^4, L^5 , and the latter are thus allowed to turn freely on the shaft extension F^2 . A detent L^{15} (Fig. 3) seated in the bracket L and arranged to engage a corresponding recess in the rock shaft L^{12} may be employed to maintain the clutch yieldingly in such disengaged or neutral position. It will now be seen that when the control handle L^{14} is thrown backwardly, the clutch L^9 is moved into engagement with the reversing gear L^5 and will thereby establish a driving connection between the fore and aft shaft G and the lay shaft F^1 , which causes the latter to be turned in a clockwise direction. Conversely, when the control handle is thrown forwardly, the clutch L^9 is brought into engagement with the reversing gear L^4 , which will drive the lay shaft F^1 in the opposite direction.

While a jaw or claw clutch, such as shown, is preferable to those of other types on account of its delicate control, it is considered advisable to incorporate in the proposed mechanism some sort of friction or slip joint which will relieve the parts of undue strain in overcoming the inertia of the magazines and shift frame; and at the same time permit the magazine selected to be properly arrested in operative position by the banking of its aligning lugs A³ on top of the gauge bars J, J¹ as before described. Such a contrivance might be arranged at any convenient point in the train of connections between the elevating screw and the driving gear G² but, in the present instance, it is applied to the inclined portion of the lay shaft F¹ (which is cut in two for the purpose) in the form of a friction coupling which comprises a pair of circular disks F⁴, F⁵ (see Figs. 1 and 2) secured to the meeting ends of the two shaft sections, and a spring-pressed detent F⁶ mounted in the plate F⁴ and engaging one or another of several recesses F⁷ formed in the opposing plate F⁵. As will be obvious without further description, if the load should exceed that for which it is adjusted to carry, the detent F⁶ will merely be forced out of the engaged recess F⁷ and permit the parts to slip.

In order to avoid the idle running of the proposed gearing during the normal operation of the machine, which would be more or less objectionable for reasons readily understood, means are provided for connecting and disconnecting the driving gear G² with and from the fore and aft shaft G as desired. Such means, as best shown in Fig. 4, consist of a clutch member G³ slidably mounted on the shaft G and a corresponding clutch member G⁴ secured to the gear G², the member G³ being splined to the shaft G by a pin and slot connection G⁵, G⁶, and adapted when moved rearwardly to engage the member G⁴. In this connection, it will be noted by reference to Fig. 4 that the gear G² is loosely mounted on the shaft G and is only connected thereto when the clutch members are engaged. The movement of the clutch member G³ into and out of engagement with the gear G² is controlled by a push and pull rod G⁷ formed at its inner end with an annular groove G⁸, wherein engages the pin G⁵, and provided at its outer or exposed end with an operating knob G⁹. A flat spring G¹⁰, secured to the bracket L and arranged to cooperate with a pin G¹¹ projecting from said knob, serves to lock or maintain the clutch in its active position when the power mechanism is operating.

The operation of the parts will now be clear. Assuming the upper magazine to be in operative position and the reversible gear mechanism to be idle, if one of the lower

magazines be selected for use, the knob G⁹ is first pushed in to connect the reversing mechanism with the assembling drive shaft G and given a partial turn to move the pin G¹¹ into engagement with the retaining spring G¹⁰. Pressure is now applied with one hand to the lever J⁴ which controls the movement of the gauge bars J, J¹, and, with the other hand, the clutch control handle L¹⁴ is rocked rearwardly to engage the clutch L⁹ with the now moving gear L⁵. A driving connection is thus established as before described, which causes rotation of the screw F to elevate the magazines. As the magazines start to move up, the gauge bars are released, and continued pressure on the lever J⁴ withdraws them to their inactive position out of the path of the lugs A³. When the magazine selected has reached a point slightly above its normal operative position, the lever J⁴ is released and the actuating springs J² draw the gauge bars into their active position with their upper ends beneath the aligning lugs of said magazine. The control handle L¹⁴ is now rocked to its extreme forward position to reverse the direction of rotation of the screw and lower the magazines until the aligning lugs A³ settle down upon the tops of the gauge bars J, J¹; the friction coupling of the lay shaft F¹ thereafter or until the control button is returned to its upright neutral position serving by the slippage which it permits to prevent damage to the parts that might otherwise occur. When a change of magazines necessitates a lowering of the shift frame, the latter must first be raised slightly in the manner just stated to free the gauge bars J, J¹ preparatory to their withdrawal. The clutch L⁹ is then moved into engagement with the gear L⁴ and held there until the desired magazine is arrested by the gauge bars, the latter meanwhile having been released in time to resume their normal position for engagement with the aligning lugs A³ of the selected magazine.

It will be understood that while the shafts F² and G, as herein constructed, constitute new elements that are particularly adapted to the proposed mechanism, the main structure of the machine is left unchanged and the application of the present improvements to machines of the type described merely involves a substitution of the bracket L, the drive shaft G, and the shaft F² for the old parts previously employed.

Having thus described my invention, its construction and mode of operation, what I claim and desire to secure by Letters Patent of the United States, is as follows:

1. In a linotype machine, the combination with a plurality of magazines, a shift frame wherein the magazines are mounted, and a screw for raising and lowering the shift frame to bring a selected magazine into oper-

ative position, of means for rotating the screw comprising the intermediate shaft, a shaft driven thereby, a lay shaft geared to the screw, and intermediate reversible gear mechanism for connecting the lay shaft with said driven shaft, whereby the screw may be rotated in one direction or the other as desired.

2. In a linotype machine, the combination 10 with a plurality of magazines, a shift frame wherein the magazines are mounted, a screw for raising and lowering the shift frame to bring a selected magazine into operative position, the intermediate shaft, and the assembler pulley shaft driven thereby, of means 15 for rotating the screw including a gear mounted on the pulley shaft, a lay shaft geared to the screw, and intermediate reversible gear mechanism for connecting the lay shaft with said gear, whereby the screw 20 may be rotated in one direction or the other as desired.

3. In a linotype machine, the combination 25 with a plurality of magazines, a shift frame wherein the magazines are mounted, a screw for raising and lowering the shift frame to bring a selected magazine into operative position, the intermediate shaft, and the assembler pulley shaft geared thereto, of means 30 for rotating the screw including a gear driven by the assembler pulley shaft, a lay shaft geared to the screw, intermediate reversing gears, and a hand-controlled jaw clutch for operatively connecting and disconnecting the 35 lay shaft with and from said driven gear as desired.

4. In a linotype machine, the combination 40 with a plurality of magazines, a shift frame wherein the magazines are mounted, and a screw for raising and lowering the shift frame to bring a selected magazine into operative position, of reversible gear mechanism for rotating the screw in one direction or the other, a hand-controlled jaw clutch for connecting and disconnecting the screw with 45 and from said gear mechanism, and a friction coupling arranged between the clutch and screw.

5. In a linotype machine, the combination 50 with a plurality of magazines, a shift frame wherein the magazines are mounted, a screw for raising and lowering the shift frame to bring a selected magazine into operation, and a locating device for arresting the selected 55 magazine in its operative position, of reversible gearing for rotating the screw in one direction or the other, a hand-controlled jaw clutch for connecting and disconnecting the screw with and from said gearing, and a 60 safety friction coupling arranged between the clutch and screw to permit arresting of the magazine.

6. In a linotype machine, the combination 65 with a plurality of magazines, a shift frame wherein the magazines are mounted,

a screw for raising and lowering the shift frame to bring a selected magazine into operative position, the intermediate shaft, and the assembler pulley shaft driven thereby, of means for rotating the screw including 70 a gear mounted on the pulley shaft, a lay shaft geared to the screw, intermediate reversible gear mechanism for connecting the lay shaft with the pulley shaft gear, and a clutch for connecting and disconnecting said 75 gear with and from the pulley shaft as desired.

7. In a linotype machine, the combination 80 with a plurality of magazines, a shift frame wherein the magazines are mounted, a screw for raising and lowering the shift frame to bring a selected magazine into operative position, the transverse intermediate shaft, the fore and aft assembler pulley shaft geared thereto, and the intermediate bracket 85 wherein the shafts are mounted, of a lay shaft geared to the screw and having a forward extension supported by the intermediate bracket in parallelism to the pulley shaft, and reversible gear mechanism for connecting the pulley shaft with said shaft extension, whereby the latter may be rotated in 90 one direction or the other as desired.

8. In a linotype machine, the combination 95 with a plurality of magazines, a screw for raising and lowering the magazines to bring a selected one into operative position, a keyboard, the constantly driven transverse intermediate shaft, the fore and aft assembler pulley shaft geared thereto, and the intermediate bracket 100 wherein the shafts are journaled, of a lay shaft having an inclined portion geared to the screw and a relatively short horizontal extension arranged below the pulley shaft in parallelism thereto, intermediate reversible gear mechanism for connecting the pulley shaft with the horizontal extension of the lay shaft, and a jaw clutch 105 constituting part of said mechanism and having a control handle arranged adjacent the keyboard, whereby the lay shaft may be connected and disconnected with and from the pulley shaft as desired.

9. A combination as specified in claim 8, characterized by the fact that the inclined 115 portion of the lay shaft therein recited is provided with a friction coupling to prevent damage to the parts as the magazines are shifted from one position to another.

10. In a linotype machine, the combination 120 with a plurality of magazines, a screw for raising and lowering the magazines to bring a selected one into operative position, a keyboard, the constantly driven transverse intermediate shaft, the fore and aft assembler pulley shaft geared thereto, and the intermediate bracket 125 wherein the shafts are journaled, of a lay shaft having an inclined portion geared to the screw and a relatively short horizontal extension arranged below the pulley shaft in 130

parallelism thereto, and intermediate gear mechanism arranged at the front of the intermediate bracket for connecting the lay shaft with the pulley shaft, said mechanism including an upright shaft geared at its upper end to the pulley shaft and at its lower end to a pair of reversible gears mounted on the short extension of the lay shaft, and a

clutch having a control handle arranged adjacent the keyboard whereby either of said reversible gears may be operatively connected to the lay shaft. 10

In testimony whereof, I have affixed my signature hereto.

DAVID S. KENNEDY.
